UNITED STATES PATENT OFFICE

2,596,914

METHOD OF MAKING CONCRETE
BUILDING UNITS

Nicholas Piacentino, Atlantic City, N.J.

Application December 9, 1948, Serial No. 64,388

1 Claim.

(Cl. 25—154)

1

My invention relates to new and useful improvements in the method of making concrete units, and has for an object to provide a unit that may readily be cast or formed on the building site.

Another object of the invention is to provide a concrete unit that does away with the making of wooden forms, so that the cost of the unit is greatly reduced.

Still another object of the invention is to provide a method for making a unit that will be carried out especially at the seashore or along the coastline where the soil is largely sand.

Still another object of the invention is to provide a concrete unit wherein the flanges of the unit or slab are to be pre-cast and then set in the sand to a certain depth, and the body of the slab or unit cast so as to reduce the cost of hauling.

Still another object of the invention is to provide a concrete unit that might be said to be cast in situ, so that rather than transporting these relatively large units, a space may be marked off on the building site and the concrete delivered and the slab cast in close proximity to where the slab is to be used, to thus save the necessity of loading on trucks and hauling to the building site.

With these and other objects in view, the invention consists in a certain new and novel method and certain new constructions, as will hereinafter be more fully explained and pointed out in the claim.

Referring now to the drawings, showing a preferred embodiment of my concrete unit and the method in which it is to be made,

Fig. 1 is a perspective showing the side and bottom rails or flanges after being partly buried in the sand before the body is cast,

Fig. 2 is a sectional view taken on line 2—2 of Fig. 1,

Fig. 3 shows the further step showing the first layer of concrete having been poured between the flanges and the reinforcing screening after having been put in place,

Fig. 4 is a similar view showing the final layer of concrete having been poured,

Fig. 5 is a perspective showing two of the units in place with the joist bolted and supported between them, and

Fig. 6 is a fragmentary, enlarged, front elevation, showing the manner in which the joist and units are bolted together.

Referring now first to the method in which I form the unit or slab, there will be noticed in Fig. 1 a rail or flange 1 which is to form the flange of the complete unit 2.

2

There will also be noticed a like rail or flange 3 and these two rails 1 and 3 are similar in all respects and are to be formed of concrete and pre-formed.

5 The concrete rail 1 will have the metal (generally iron) reinforcing rod 4 (see Fig. 2) near its top, and the lower like metal rod 5, these rods 4 and 5 extending throughout the length of the rail 1 for strengthening purposes.

10 Also secured to the upper rod 4 may be seen the metal hooks or anchors 6, which are placed throughout the length of the rail 1 and these, of course, are attached to the rod 4 before the cast rail 1 is formed.

15 In a like manner, in the rail 3 there are shown the two rods 4' and 5' for strengthening purposes; and there will be like hooks or anchors 6' attached thereto.

It is to be noticed that both the rails 1 and 3 have the reduced portions 7 and 7' at their upper ends, the purpose of these reduced portions being that when two units are bolted to each other (as shown in Fig. 5 and later to be mentioned) they will hold the joists or beams that are used to support the ceiling or roof, etc.

20 I also preferably provide a bottom flange 8 that is pre-cast; and this in turn will have imbedded therein the reinforcing rods 9, and there may be a series of apertures 10 in this bottom flange 8 so that this unit 2 may be bolted to a foundation (not shown).

25 Also, in the cut-out portions 7 and 7' of the side rails 1 and 3, there will be the apertures 11 for the reception of bolts 11'.

30 After these side rails 1 and 3 are pre-cast, as well as the bottom flange 8, they will be trucked or transported to the building site; and, where the soil is of a sandy nature, as along the Atlantic Seaboard, ground space may be cleared and levelled off and the side rails 1 and 3 buried in the sand for about half their depth, as may be seen in Figs. 2, 3 and 4. Then the bottom flange

35 8 is placed between the rails 1 and 3 (as shown in Fig. 1) and a metal gate 12 placed at the upper ends of the rails, that is, adjacent the ends of the cut-out portions; and a thin layer of concrete 13 (see Fig. 3) poured on the sand between these rails 1 and 3 and the bottom flange 8, the metal gate 12 at the top limiting the flow of wet concrete at this end.

40 Immediately after the layer 13 is poured, the reinforcing screening 14 will be imbedded in the wet concrete and tied or secured to these anchors 6, heretofore mentioned, to form a strong binding; and after this wire reinforcement 14 is in, immediately there will be poured another layer

of concrete 15 (see Fig. 4) on top of the screening 14 in the previous layer 13, so that the wire reinforcing 14 is completely imbedded, and thus not affected by dampness or the atmosphere.

After the unit is thus cast, of course it hardens; and the gate 12 will be removed; and there is now formed a slab or unit, as shown in Fig. 5, of great strength, provided with shoulders at its upper end to support the beams or joists 16.

As heretofore mentioned, bolts 11' will be fastened through the adjacent flanges of adjacent units and additional bolts may be used throughout the height of the slab.

It will also be understood that if it is not desired to have the bottom flange 8 cast integral with the unit, this might be dispensed with; and then, of course, in the molding, a gate similar to gate 12 would be used at the lower end.

Thus, it will be seen that there is no necessity of making up wooden forms to cast these slabs, the only forms necessary being those that are used to pre-cast the flanges 1 and 3 and the bottom flange 8, if it is desired to use one.

It will also be understood that these units or slabs may be of any desired height, depending on the height of the building; and their width may be figured out before they are made, so that the number of them to be used will depend on the width of the building.

Also, if desired, a material to form an expansion joint may be placed between the adjacent units as shown at 20, in Figs. 5 and 6.

By using a bottom flange 8, the slab may be bolted to the foundation; and it is of course understood that, although not shown, if desired a flange might be cast across the upper end of the unit.

From the foregoing, it will be seen that I have provided a slab or unit that may be used for the side walls of a building, might equally well be used for a flooring or ceiling, and likewise used for a roof; and the units after once being cast, quickly bolted in position.

Furthermore, it will be seen that by doing away with the use of wooden forms, it saves considerable cost for carpenters.

Finally, it will be seen that by forming the block right at the building site, all that has to be transported are the side rails or flanges and the bottom rail or flange, if one is used, so that the "Ready-Mix" concrete may be delivered right to the building site and the forms cast on the

ground, thus saving the transportation of slabs that may weight several hundred pounds apiece.

Also, it will be seen that after the sandy soil is once levelled off, any desired number of these units may be cast at the same spot, it not being necessary to build a wooden form each time the unit is cast, which procedure is necessary now with the ordinary form of making concrete slabs, etc.

Many slight changes might be made without departing from the spirit and scope of the invention.

Having thus described my invention, that is, the unit and the method of making the same, what I claim as new and desire to secure by Letters Patent is:

The method of forming a concrete building unit having side flanges and a bottom or end flange, which consists in preforming a concrete side flange having a longitudinally extending reinforcement with integral anchors projecting laterally through the flange, sinking a pair of side flanges so formed in spaced relationship, and with their anchors opposed, into soil for about half their depth, placing a bottom or end flange between one end of the side flanges and a gate against the other end of the side flanges, pouring a relatively thin layer of concrete between all the flanges and the gate to form part of the body portion of the unit, placing a wire reinforcement between the flanges and imbedding same in the wet concrete and securing same to the laterally projecting anchors, placing a further layer of concrete over the wire reinforcement and levelling the same off flush with all the flanges to thus form the complete unit, letting the unit harden and removing the gate.

NICHOLAS PIACENTINO.
